COIL WINDING MACHINE

Robert M. Conklin, West Newbury, Mass., assignor
to Western Electric Company, Incorporated,
New York, N. Y., a corporation of New York

Application August 22, 1945, Serial No. 611,934

7 Claims. (Cl. 242—4)

1

This invention relates to coil winding machines, particularly those of the toroidal winding type and the primary object of the invention is a machine of this type which is capable of winding coils of very small size and weight.

Present standard machines of this general type have winding rings equipped with wire guides and supplies of wire and traveling in circular paths which extend through the annular cores upon which the wires are being wound. During the travel of the wire guide in each instance to the point farthest from the core, a length of wire is withdrawn from the ring to form one turn on the core. This length of wire in standard practice forms a loop during the travel of the wire guide from its position farthest from the core to its position after it has passed through the core. This loop is carried around and then suddenly pulled tight on the core thereby subjecting the wire to a sudden and abnormally high tension which is a limiting factor in the size of wire which can be used successfully. Before the loops are tightened, the wire is free to whip from side to side and frequent overlapping of the turns occurs often to the extent of increasing the cross-sectional area of the coil by twenty or thirty per cent.

It is, of course, desirable to make these coils as small and compact as possible and this is particularly true when they are to be used in military communication systems where minimum volume and weight are of primary importance.

The size of a coil of given electrical constants is largely determined by the diameter of the wire used and the size of central aperture of the finished coil. The aperture cannot be reduced beyond the diameter required for the passage of the wire guiding structure and with existing machines the wire must be at least number 38 A. W. G. in order to withstand the tension imposed on it when the loops are tightened.

Attempts have been made to control the loops by pulling them between spring-backed plates before the wire passes to the core, but insofar as applicant is aware, none of these expedients have been successful in eliminating either the overlapping of the turns or the high tension produced when the loops are tightened on the core.

In the winding machine of this invention, a shuttle carrying a supply of the wire to be wound on a core is driven at constant speed and a flyer for guiding the wire from the shuttle around the core is driven by means which tends to rotate the flyer at many times the speed of the shuttle. With this structure the wire is kept

2

under constant tension so that the formation of loops or any slack which could result in jerking action on the wire or overlapping of the turns is effectively prevented.

10 In one embodiment of the invention, the flyer is driven by compressed air around a stationary track and an open type shuttle is used thereby facilitating the operation of the machine and eliminating the cost of maintaining the segment mechanism usually used for closing the shuttle.

Alternatively, the flyer may be frictionally supported on the track and the track driven at a higher speed than the shuttle to apply to the flyer a constant accelerating force which is the 15 equivalent of that obtained in above construction by pneumatic means.

With either of these constructions, the elimination of the jerking action on the wire makes it practicable to use finer wires than could be 20 used heretofore and the elimination of the loops and the overlapped turns. The use of finer wires reduces the size of the coil not only because of the reduced bulk of the winding itself, but also because the resulting thinner winding layer permits 25 the use of a core having a smaller aperture and outside diameter. The improved efficiency in the utilization of the winding space resulting from the elimination of overlapping obviously will also reduce the bulk of the coil and these 30 two factors in combination, make it possible to produce a toroidal coil of given constants which is of much smaller bulk and weight than those which can be made with other known machines.

Other objects and advantages will be apparent 35 from the following detailed description when considered in conjunction with the accompanying drawings, wherein

Fig. 1 is a fragmentary side elevational view of a toroidal coil winding machine constituting 40 one species of the invention, portions thereof being broken away;

Fig. 2 is a similar side elevational view of the machine shown in Fig. 1 with other portions, including the shuttle, removed;

Fig. 3 is an elevational view of the other side of the machine, portions thereof being broken away;

Fig. 4 is an enlarged fragmentary sectional view taken along the line 4—4 of Fig. 1;

50 Fig. 5 is an enlarged detailed sectional view taken along the line 5—5 of Fig. 1;

Fig. 6 is a fragmentary detailed view of another species of the invention illustrating the flyer, its track and the driving means therefor;

Fig. 7 is a side elevational view of the open

shuttle for the species shown in Fig. 6 and the driving means therefor; and

Fig. 8 is a fragmentary sectional view of this species.

Referring now to the drawings, attention is first directed to Figs. 1 to 5, inclusive. In this embodiment of the invention, a housing 10 has an opening 11 near its center which extends outwardly at 12 to allow sufficient space for the annular core 14 upon which wire 15 is to be wound. The core 14 is supported by a chuck or clamp 16, which is movable by suitable means (not shown) to reversably rotate the core about its axis for substantially one-half revolution at a given speed to cause equal distribution of the wire on the core. A supply of the wire 15 is wound upon an open shuttle 18, which is of the cross-sectional contour illustrated in Figs. 4 and 5 so that it will pass through the center of the core. The shuttle 18 is described as being open due to the provision of an open portion 20 of sufficient size to allow for the mounting of the core 14 in the chuck 16 prior to the winding of the wire thereon and for the removal of the wound core from the chuck.

The inner periphery of the shuttle 18 is provided with teeth 21 which interengage teeth 22 of pinions 23, 24, 25 and 26. The pinions 23 and 24 are driven by a pinion 27 as illustrated. The teeth of the pinions 23 to 26, inclusive, are positioned between disc-like guide members 28 and 30 of the pinions, the guide members serving to straddle the teeth 21 of the shuttle at their spaced positions to maintain the shuttle in a given position during its travel in a circular path. The guide member 30 of each pinion also serves to support the shuttle due to the fact that a shoulder 31 of the shuttle rests upon the peripheries of each of these guide members. If desired, the shuttle may be provided with a frictional drive through its contact with one or both of the guide members 28 and 30 of the pinions 23 to 26, inclusive. In this instance, the pinions 23 and 24 may be driven by the pinion 27, or, if desired, all four pinions 23 to 26, inclusive, may be driven thereby, the driving force being transferred from the intermediate pinions through the frictional engagement of their guide members with the shuttle. Shafts 33 to 37, inclusive, are provided for the pinions 23 to 27, inclusive, the shaft 37 not being driven by suitable power means (not shown).

The housing 10 has a compartment 40 which extends in an incomplete circle about the opening 11 as illustrated in Figs. 3 and 4. A supply line 41, for supplying a fluid such as air under pressure to the compartment 40, may be connected to any suitable supply such as a variable delivery pump 42 under the control of a valve 43 to supply the compartment with fluid or air under variable pressures. A circular arrangement of exhaust ports 44 provide connections between the compartment 40 and a chamber 45. This circular arrangement of exhaust ports will direct jets of air in directions to drive a flyer 48 in a counterclockwise direction. Exhaust ports 47 open the chamber 45 to the atmosphere at numerous points.

The flyer includes an arcuate member 49 slidably mounted in grooved tracks 50 in the housing 10. These tracks 50 are formed in the housing in opposite walls of an annular passageway 51 which extends in an incomplete circle for the flyer. A movable segment or element 53 grooved as at 54 to receive the flyer completes the circular

track for the flyer at the open portion 12 of the housing. One end of the segment 53 is pivoted at 55 while the other end is removably held in position by a spring pressed plunger 56. When the segment is in its open position, the core 14 may be inserted in place and removed from the chuck 16.

Returning to the detailed structure of the flyer, it will be noted that cup shaped members 58, mounted at spaced positions upon the member 49, provide pockets for the jets of air, to facilitate in the acceleration of the flyer in a counterclockwise direction (Figs. 1 and 2). A guide 60 is mounted upon the opposite side of the member 49 and extends over the shuttle as illustrated in Fig. 5. Through the aid of the guide 60, particularly a groove 61 therein, the wire is free to pass from the shuttle and around a sheave 62. The sheave 62 may be supported by anti-friction bearings or other suitable means on the flyer member 49.

In preparing this species of the invention for operation, the auxiliary track section 53 is released from the plunger 56 and moved outwardly about its pivot 55 for the mounting of a core 14 in the chuck 16. The track portion is then returned to its closed position as shown in Fig. 2. At this time, or prior to the mounting of the core in the chuck, the shuttle 18 is provided with a supply of the wire 15 by rotation of the shuttle in a clockwise direction. The free end of the wire 15 is then threaded from the shuttle, through the groove 61 in the guide 60, around the sheave 62 and is secured in any suitable manner to the core 14. The machine is now ready for operation. The valve 43 is opened to direct air under pressure into the compartment 40 and from the compartment through the exhaust ports 44 in directions to cause acceleration of the flyer 48 in a counterclockwise direction (Fig. 2). At this time, the shuttle 18 is driven at a constant rate of speed in the same direction. The force of the air under pressure applies an accelerating force to the flyer tending to accelerate the flyer at a speed many times the speed of rotation of the shuttle. The force applied to the flyer is of a flexible nature, however, so that the movement of the flyer will be under the control of the wire 15. Furthermore, by applying a constant force to the flyer with the jets of air, a constant tension is created in the wire. Furthermore, the application of the constant tension to the wire eliminates the formation of any slack or loop in the wire which might otherwise result in jerking of the wire as each turn on the core is completed. By applying a constant tension on the wire and guiding the wire in its entire movement about the core in forming each turn, it is not possible for the wire to whip to one side or the other to cause over-laying of the turns, but instead the turns are laid uniformly.

The species of the invention shown in Figs. 6 through 8, inclusive, embodies an open shuttle 10 identical in structure to the shuttle 18 and provided with a similar driving means. The driving means in this instance includes a drive gear 71, driven gears 72 and 73 and idler gears 74 and 75. If desired, the gears 74 and 75 may also be driven. The teeth of the gears 72 and 73 interengage teeth 76 mounted at the inner periphery of the shuttle. The gears 72 to 75, inclusive, are provided with guide members 78 and 79 which serve to maintain the shuttle in a fixed path extending substantially through the center of a core 80. The shuttle is formed with a shoulder 81

which rests upon the outer peripheries of the members 79 of the gears 72 to 75, inclusive. If desired, the gears 72 to 75, inclusive, may function to provide a frictional drive for the shuttle, through the members 79 and the shoulder 81 of the shuttle, in place of the positive connection of the teeth 76 of the shuttle and the teeth of the gears.

This species of the invention is also similar to the species shown in Figs. 1 to 5, inclusive, in that a continuous track 83 is provided for the flyer 84 with a removable segment 85 to facilitate in the mounting of the core 80 in its chuck 86. The difference lies in the detailed structure of the flyer and in the fact that the track is driven at a velocity many times that of the shuttle to apply a driving force to the flyer 84 which is similar to the force applied to the flyer 48 by the jets of air. The driving means for the track 83 in this instance is similar to the driving means for the shuttle. A driving gear 87 drives gears 88 and 89 to drive the track, the latter including the segment 85 having teeth 90 formed on the inner periphery thereof. Companion gears 91 and 92 assist the gears 88 and 89 in supporting the track. If desired, the gears 91 and 92 may also be driven. Furthermore, a frictional driving means may be provided between the gears and the track as previously suggested regarding the shuttle. By viewing Fig. 8, it will be noted that the gears 88, 89, 91 and 92 are provided with guide members 94 and 95 which serve to maintain the track and its segment for rotation in a given path which extends with the shuttle, substantially through the center of the core 80. Furthermore, shoulders 96 of the track and its segment rest upon the outer peripheries of members 95 to support the track in its desired position.

The flyer in this embodiment includes a guide 49 with a groove 99 to receive the wire from the shuttle and direct it to a sheave 100. The guide and the sheave are supported by the flyer 84 which rides in annular grooves 101 in the track 83 and the segment 85. The portion of the flyer 45 at the right of the sheave 100 includes arcuate resilient members 102 which are initially forced toward each other to position them in their grooves. The legs or members 102 of the flyer therefore create frictional contacts with the walls 50 of the grooves 101 so that the driving force of the track will urge the flyer forwardly in a counterclockwise direction, its speed of movement being variable, however, under the control of the wire 103.

During the operation of this species of the invention, the shuttle, holding the supply of wire, is driven at a constant rate of speed and the track 83 is driven at a much faster rate of speed equivalent to or greater than the speed necessary to cause the flyer to continuously apply a constant tension of a given value on the wire. During the travel of the flyer, particular interest being in the wire controlling end thereof, after it passes through the core and until it reaches the farthest position from the core, a length of wire sufficient for the next turn on the core is withdrawn from the shuttle. At this time, the flyer is moving at approximately the same speed as the shuttle, although the track is traveling at a higher velocity, the flyer being retarded by the wire which is freed from the shuttle at the speed of travel of the shuttle. During the travel of the flyer from its position farthest from the core and until it again passes through the 65 70 75 core, there would be a formation of a loop in the wire if the flyer continued to travel in the same speed as the shuttle. This is avoided, however, by the speed and driving force of the track being sufficient to rotate the flyer at the maximum speed desired. This is made possible through the frictional contact of the flyer with the track, to maintain the constant tension on the wire and guide it uniformly about the core.

Although specific embodiments of the invention have been shown and described, it will be understood that they are but illustrative and that various modifications may be made therein without departing from the scope and spirit of this invention as defined by the appended claims.

What is claimed is:

1. In a toroidal coil winding machine, a support for an annular core on which a wire is to be wound, a circular shuttle for a supply of the wire, 20 means to support the shuttle in a position at right angles to the core for rotation in a circular path extending substantially through the center of the core and about a fixed axis, a flyer under the control of the wire to distribute the wire from the shuttle around the core, a continuous track for the flyer spaced from the shuttle and extending in a circular path through the core, and means for supplying a driving force for the flyer to drive the flyer at varying speeds under the control of the wire and to apply a constant tension on the wire.

2. In a toroidal coil winding machine, a support for an annular core on which a wire is to be wound, an open shuttle having a supply of wire thereon, means to support the shuttle in a position at right angles to the core for rotation in a circular path extending substantially through the center of the core and about a fixed axis, a flyer under the control of the wire to distribute the wire from the shuttle around the core, a continuous track for the flyer spaced from the shuttle and extending in a circular path through the core, and means for supplying a driving force for the flyer to drive the flyer at varying speeds under the control of the wire and to apply a constant tension on the wire.

3. In a toroidal coil winding machine, a support for an annular core on which a wire is to be wound, an open partially circular shuttle having a supply of wire thereon and a shoulder adjacent its inner periphery, driving means for the shuttle including rotatable members engaging the said shoulder to support the shuttle and guide the shuttle in a circular path extending substantially through the center of the core and about a fixed axis, a flyer under the control of the wire to distribute the wire from the shuttle around the core, a continuous track for the flyer spaced from the shuttle and extending in a circular path through the core, and means for supplying a driving force for the flyer to drive the flyer at varying speeds under the control of the wire and to apply a constant tension on the wire.

4. In a toroidal coil winding machine, a support for an annular core on which a wire is to be wound, a circular shuttle for a supply of the wire, means to support the shuttle in a position at right angles to the core for rotation in a circular path extending substantially through the center of the core and about a fixed axis, a flyer under the control of the wire to distribute the wire from the shuttle around the core, a stationary circular track for the flyer, and means to drive the flyer at variable speeds in a circular path controlled

7 by the track to create a constant tension on the wire.

5. In a toroidal coil winding machine, a support for an annular core on which a wire is to be wound, a circular shuttle for a supply of the wire, means to support the shuttle in a position at right angles to the core for rotation in a circular path extending substantially through the center of the core and about a fixed axis, a flyer having a laterally extending member, movable in a circular path through the core under the control of the wire to distribute the wire from the shuttle to the core, a stationary circular track for the flyer, and means to direct a fluid under pressure to the said member of the flyer 10 to drive the flyer at varying speeds under the control of the wire and to apply a constant tension on the wire.

6. In a toroidal coil winding machine, a support for an annular core on which a wire is to be wound, a circular shuttle for a supply of the wire, means to support the shuttle in a position at right angles to the core for rotation in a circular path extending substantially through the center of the core and about a fixed axis, a flyer 20 under the control of the wire to distribute the wire from the shuttle around the core, a stationary track for the flyer extending in a partially

8 circular path, a track segment mounted to extend through the core and to complete the circular path for the flyer.

7. In a toroidal coil winding machine, a support for an annular core on which a wire is to be wound, a circular shuttle for a supply of the wire, means to support the shuttle in a position at right angles to the core for rotation in a circular path extending substantially through the center of the core and about a fixed axis, a circular rotatable track in a circular path through the core, a flyer having resilient legs supported frictionally in the track and movable thereby under the control of the wire to distribute the wire from the shuttle around the core, and means to drive the track at a speed faster than the shuttle to cause the flyer to travel at a speed faster than the shuttle when moving toward the core to maintain constant tension on the wire.
